2,592,460

RETRIEVER FOR SUBMERGED ARTICLES

Layton E. Perkins, Milwaukee, Wis.

Application December 1, 1949, Serial No. 130,419

9 Claims. (Cl. 9—9)

1

This invention relates to improvements in retrievers for submerged articles.

There are many instances wherein it is necessary or desirable to locate and retrieve articles which are submerged in relatively deep water. This is frequently impossible without resort to diving equipment, and the latter entails a considerable expense. In my Patent Number 2,479,021, issued August 16, 1949, is disclosed a retriever for submerged relatively light weight articles, said device being relatively simple and connectable to articles which are susceptible of loss overboard.

The weight of the article which may be retrieved by the retriever disclosed in my Patent 2,479,021 is necessarily limited to the strength of the cord incorporated therein. In order to maintain a desirable relatively small unit size, it is necessary to use relatively light weight cord in the retriever of my prior patent, and for this reason, said retriever is best adapted for retrieving relatively light weight articles such as casting rods, guns or the like.

With the above in mind it is a general object of the present invention to provide an improved retriever for relatively heavy submerged articles, such as boats, airplanes, mines, large outboard motors or the like.

A further object of the invention is to provide an improved retriever of the class described wherein the weight of the article which may be retrieved is not limited by the strength of the cord incorporated in the retriever.

A further object of the invention is to provide an improved retriever which is provided with means for preventing operation until after the retriever has been submerged to a predetermined depth.

A further, more specific object of the invention is to provide an improved retriever of the class described comprising a sleeve member adapted to be permanently connected to the article to be retrieved and two buoys which form caps for the opposite ends of said sleeve member, there being a relatively long line connecting said buoys through said sleeve member, and there being means in the sleeve member responsive to the action of water thereon for simultaneously ejecting the buoys from the sleeve member.

A further specific object of the invention is to provide an improved retriever of the class described wherein the buoys normally form watertight covers for the open ends of the sleeve member, and wherein the sleeve member is provided with an intermediate opening having a

2

spring loaded valve normally sealing said opening, said valve being responsive to a predetermined pressure to permit water to enter said body after the retriever has been submerged a predetermined depth.

A further, more specific object of the invention is to provide a device of the class described in which the buoys of the device are normally held in position on the sleeve member and against the tension of a pair of springs by a replaceable cartridge, the retrieving line being positioned within the cartridge, and the cartridge comprising spaced heads which are normally connected by material which is readily ruptured or disintegrated when submerged in water.

A further specific object of the invention is to provide an improved retriever of the class described which, upon submersion in water, releases the buoys thereof so that they may travel up to the surface of the water, said buoys being interconnected by a retrieving line which extends through the sleeve member, whereby a relatively heavy line may thereafter be connected to one end of the retrieving line in place of one of the buoys and may be drawn down through the sleeve member and back up to the water surface by a pull on the opposite end of the retrieving line. Thus the recovery of a relatively heavy, submerged article may be accomplished by lifting said article with relatively heavy rope.

A further object of the invention is to provide a device of the class described which is positive in operation, neat in appearance, inexpensive to manufacture, and well adapted for the purposes described.

With the above and other objects in view, the invention consists of the improved retriever for submerged articles, and all of its parts and combinations, as set forth in the claims, and all equivalents thereof.

In the drawing accompanying and forming a part of this specification, illustrating one complete embodiment of the preferred form of the invention, and wherein like characters of reference designate the same parts in all of the views:

Fig. 1 is a fragmentary side elevational view of the improved retriever, parts being broken away and shown in longitudinal vertical section; and

Fig. 2 is a view illustrating a submerged boat on the bottom of a lake, the sleeve member of the improved retriever being connected thereto, and the buoys of the improved retriever being on the surface of the water and interconnected by a line which extends through the said sleeve member.

Referring more particularly to Fig. 1 of the drawing, the numeral 5 indicates a sleeve member which is open at both ends and which is formed with an internal annular shoulder 6 intermediate the length thereof. Telescopically positioned in the opposite open ends of the sleeve member 5 are buoys 7 and 8. The buoys 7 and 8 are each preferably formed of a cylindrical cup shaped member 9 having a wall 11 at one end thereof and of a cup shaped cover member 10 closing the open outer end of the cup shaped member 9 and sealingly and fixedly connected thereto, as by welding or the like, so that said buoys will float. In lieu of the hollow metal buoys illustrated and described, buoys of wood, cork or other buoyant material may be used.

Secured to the inner side of the wall 11 of the buoy 8 is a U-shaped spring clip 12 having oppositely disposed legs 13. The legs 13 are apertured, as at 14, to receive a transverse pin 15.

An elongated replaceable cartridge 16 extends longitudinally within the sleeve member 5. The cartridge 16 includes a pair of oppositely disposed heads 17 and 18 which are preferably circular in shape. The heads 17 and 18 are connected by a release member 19 which is preferably tubular and cylindrical, and which is glued or otherwise secured to the heads as at 20 and 21. The member 19 may be formed of material which is weakened or disintegrated by the action of water.

The inner ends of the heads 17 and 18 are formed with portions of reduced external diameter to receive thereon tubular cylindrical cardboard containers 22 and 23, which are positioned within the tubular release member 19, and which have their inner ends abutting, as shown at 24. Positioned within the container 23 is a roll 25 of relatively light weight line which is connected at one end to the pin 15 as shown. Positioned in the container 22 is a roll of relatively light weight line 26 which has one end interconnected with the opposite end of the roll 25, as at 27. The opposite end of the roll 26 is connected to a pin 28 extending transversely through the head 17 as shown.

Fixed to the outer wall of the head 17 are a plurality of hook members 29. Fixed to the inner surface of the wall 11 of the buoy 7 are a plurality of pivotally mounted bell crank levers 30 having hook portions 31 on the axially extending arms thereof engageable with the hooks 29, as shown. A flat spring 32 preferably engages the radially extending arms of the levers 30 and urges the hook members 31 into engagement with the hooks 29. Positioned within the sleeve member 5 and normally located in compressed condition between the inner wall 11 of the buoy 7 and one side of the internal shoulder 6 is a helical spring 33. Similarly positioned between the inner wall 11 of the float 8 and the other side of the shoulder 6 is a helical spring 34.

The sleeve member 5 is formed adjacent the internal shoulder 6 with an external generally cylindrical boss 35 having a cylindrical recess 36 therein. A pair of apertures 37 and 38 afford communication between the recess 36 and the interior of the sleeve 5. The boss 35 is formed at its upper end with an inwardly projecting annular flange 39 as shown. Positioned in the recess 36 is a helical spring 40, and positioned at the outer end of the spring 40 and urged into sealing engagement with the annular flange 39 is a pad or valve disk 41.

The inner end of the head 18 may be formed 75

with a recess 42 to receive a quantity of dye 43 which may be in capsule, pill or powdered form, said dye being held in the recess 42 by a layer 44 of paper or the like covering said recess and cemented to the inner wall of the head 18 adjacent the margin of the recess 42. The layer 44 may be of any material which is disintegrable by water contact, such as ordinary filter paper or the like.

10 In use, the improved retriever is connected to an article, such as the boat shown in Fig. 2, by any suitable means. Upon submergence of the article to which the retriever is connected, no water enters the body 5 of the retriever until said retriever is submerged to a predetermined depth, since the buoys 7 and 8 form watertight covers for the ends of the sleeve 5. The predetermined depth is that depth at which the water pressure moves the disk 41 inwardly off of its seat on the flange 39 of the boss 35 and against the tension of the spring 40.

When the disk 41 is pushed inwardly away from its seat, water is permitted to flow around the edges of said disk 41, through the recesses 35, 37 and 38 and into the interior of the body 5. Upon exposure to the water entering the body 5, the release member 19 begins to disintegrate and soon it is no longer able to withstand the forces exerted by the springs 33 and 34. As a result, the release member 19 will break along the line of abutment 24 of the cartridge members 22 and 23, and the springs 33 and 34 will then expand and eject the buoys 7 and 8 from the ends of the body member 5. The floats will then rise to the surface of the water by reason of their buoyancy and will assume positions such as those shown in Fig. 2.

As an aid in locating the submerged article and the buoys 7 and 8, the paper 44 on the head 18 will disintegrate upon exposure to the water 40 and release the dye 43. The dye will then color a relatively large area of the water surrounding the buoy 8 and render said area much easier to locate.

In travelling toward the surface, the buoys 7 and 8 unwind the rolled up lines 25 and 26, respectively. Since the lines 25 and 26 are interconnected, as at 27, the buoys 7 and 8 are interconnected by a single line which also passes through the sleeve member 5. A relatively heavy rope or cord may then be tied to the upper end of either of the lines 25 or 26 in place of the buoy connected thereto. A pull on the line connected to the remaining floating buoy will then cause the heavier rope to be pulled down through the sleeve member 5 and back up to the surface. The submerged boat or other article can then be raised by means of the heavier rope.

The cartridge 16 is replaceable, and a new cartridge can be connected to the buoy 8 by removing the pin 15, replacing the head 18 with the head 18 of a new cartridge 16, and then replacing the pin 15 in the apertures 13 and in the diametrical aperture in the head 18 of the new cartridge.

For assembly purposes the connection hooks 29 and 30 are used to connect the buoy 7 with the head 17 of the cartridge 16. The improved retriever may be assembled by placing the springs 33 and 34 in the body 5, inserting the cartridge 16 (which has been previously connected to the buoy 8) into one end of the sleeve 5, and then inserting the buoy 7 into the opposite end of the sleeve 5. Pushing the buoys inwardly causes the hooks 30 to engage the hooks 29 and lock the apparatus in assembled condition.

The improved retriever forms a compact unit

which is simple in construction and easy to manufacture. The maximum weight of the article which may be recovered by the improved retriever is not limited by the strength of the lines 25 and 26, and therefore relatively heavy submerged articles can be recovered. The operation of the improved retriever is positive, and said retriever simply and inexpensively eliminates the necessity of employing diving equipment for the recovery of submerged articles.

It is obvious that the disc 41 and the spring 46 may be eliminated where it is desired that the retriever operates regardless of the depth of the water in which it is submerged.

Various other changes and modifications may be made without departing from the spirit of the invention, and all of such changes are contemplated as may come within the scope of the claims.

What I claim is:

1. A retriever comprising: a tubular body; a pair of buoys; releasable connection means connecting said buoys and normally maintaining said buoys in engagement with said body, said means including a release member having a portion which is disintegratable when acted upon by water to cause release of both of said buoys; and a line extending through said tubular body and connected at each end to a separate one of said buoys, said line having a normally compacted portion between its ends.

2. A retriever comprising: a tubular body; a pair of buoys; releasable connection means connecting said buoys and normally maintaining said buoys in engagement with said body, said means including a release member having a portion which is disintegratable when acted upon by water to cause release of both of said buoys; a line extending through said tubular body and connected at each end to a separate one of said buoys, said line having a normally compacted portion between its ends; and spring means positioned to urge said buoys away from said body and operable in response to release of said buoys to eject said buoys from said body.

3. A retriever comprising: a tubular body having open ends; a pair of buoys; releasable connection means in said body connecting said buoys and normally maintaining said buoys in the open ends of said body, said means including a release member having a portion which is disintegratable when acted upon by water to cause release of both of said buoys; a line extending through said tubular body and connected at each end to a separate one of said buoys, said line having a normally compacted portion between its ends; and spring means in said body positioned to urge said buoys outwardly from said body openings and operable in response to release of said buoys to eject said buoys from said body and openings.

4. A retriever comprising: a tubular body having an internal annular shoulder and having open ends; a pair of buoys; a line extending through said tubular body and connected at each end to a separate one of said buoys, said line having a normally compacted portion between its ends; a first spring in said body positioned between said annular shoulder and one of said buoys; and a second spring in said body positioned between said annular shoulder and the other of said buoys; and releasable connection means in said body connecting said buoys and normally holding said buoys in the open ends of said body in a manner to com-

press said springs, said means including a release member which is positioned so as to be subjected to the expanding stresses of said springs and which is constructed of material which is unable to resist said stresses and therefore ruptures when acted upon by water; said springs, upon rupture of said release member, being operable to eject said buoys from said body in opposite directions.

5. A retriever comprising a tubular body having spaced openings communicating with the interior thereof; a pair of buoys; a connection member in said body normally connecting said buoys and normally maintaining said buoys in position in said openings; spring means normally in compressed condition and normally urging said buoys away from said body, said connection member being subjected to the expanding stresses of said spring means and being constructed of material which is unable to resist said stresses when acted upon by water; and a line extending through said tubular body and connected at each end to a separate one of said buoys.

6. A retriever comprising a cylindrical tubular body having open ends; a pair of buoys; a connection member in said body normally connecting said buoys and normally maintaining said buoys in position in said open ends; spring means normally in compressed condition and normally urging said buoys in opposite directions away from said body, said connection member being subjected to the expanding stresses of said spring means and being constructed of material which is unable to resist said stresses when acted upon by water; and a line extending through said tubular body and connected at each end to a separate one of said buoys.

7. A retriever comprising a tubular body having open ends; a pair of buoys; a connection member in said body normally connecting said buoys and normally maintaining said buoys in position in said openings; a spring means in said body normally in compressed condition and normally urging said buoys in opposite directions away from said body, said connection member being subjected to the expanding stresses of said spring means and being constructed of material which is unable to resist said stresses when acted upon by water; and a line extending through said tubular body and connected at each end to a separate one of said buoys.

8. A retriever comprising: a tubular body having open ends; a buoy normally forming a watertight cover for each of said open ends; means within said body normally holding said buoys in sealing engagement with said body in said open ends, said means being releasable in response to the action of water thereon; a line connecting said buoys; an opening in the sidewall of said body; and a valve normally sealing said second opening and responsive to a predetermined pressure to admit water into the interior of said body when the retriever is submerged.

9. A retriever comprising: a tubular body having open ends and having an internal annular shoulder intermediate said ends; a first helical spring positioned in said body with one end in abutment with said annular shoulder, said spring having an outer diameter not substantially smaller than the inner diameter of 75 the body and said shoulder having an inner

diameter not substantially smaller than the inner diameter of said spring; a second spring substantially identical with said first spring positioned in said body with one end in abutment with the opposite side of said annular shoulder; a pair of buoys; a line extending through said tubular body and connecting said buoys, said line having a normally compacted portion between its ends; and a connection member normally connecting said buoys and normally holding said buoys in the open ends of said body in a manner to compress said springs, said connection member being subjected to the expanding stresses of said springs and being constructed of material which is unable to resist said stresses when acted upon by water. **15**
